GIN POLE

Harold J. Martin, Chicago, Ill., assignor to The
L. E. Myers Co., Chicago, Ill., a corporation of
Delaware

Application July 3, 1940, Serial No. 343,752

3 Claims. (Cl. 254—143)

The invention relates to improvements in gin poles adapted for use in simple hoisting operations in the field, the primary object of the invention being the provision of a simple and effective construction of the character indicated, so arranged and mounted as to be capable of ready transportation and quick erection and use in the field, and which is of simple construction and highly efficient in use.

Other objects will appear hereinafter.

The invention consists of the combinations and arrangements of parts hereinafter described and claimed.

The invention will be best understood by reference to the accompanying drawings forming a part of this specification and in which:

Fig. 1 is a side elevation of a gin pole arrangement embodying the invention;

Fig. 2, an enlarged side view, shown partially in section, of the upper end of the gin pole;

Fig. 3, a plan view of a guy bracket employed at the top of the pole;

Fig. 4, an enlarged transverse section taken substantially on line 4—4 of Fig. 1;

Fig. 5, a section taken substantially on line 5—5 of Fig. 4;

Fig. 6, a transverse section taken substantially on line 6—6 of Fig. 4;

Fig. 7, an enlarged partial side view of the medial portion of the gin pole; and

Fig. 8, a view taken at right angles to Fig. 7.

The embodiment of the invention illustrated in the drawings comprises a truck body 10 of any usual or desired construction, and running at one end on caterpillars 11. The other end of the body 10 is connected with a caterpillar tractor 12 equipped with a suitable engine 13 as indicated.

A base member in the form of a transverse pipe or tube section 14 is mounted transversely of the truck body 13 the ends of said base member being provided with cuffs or collars 15 resting in the ends of a channelled support 16 and firmly held therein by means of U-bolts 17 as shown. A U-shaped bracket 18 is arranged as indicated to embrace the base member 14 and the lower end of a tubular gin pole section 19 is pivotally secured in the bracket 18 by means of pivot bolt 20 whereby said gin pole section is pivotally mounted on the truck 10 to swing in either direction, the lower end 21 of said section being rounded as shown to facilitate such pivoting.

An upper tubular gin pole section 22 is arranged as shown to fit within and telescope with the section 19, the upper end of the section 19

being provided with a guide ring 23, to hold the section 22 centrally within it. The lower end of section 22 is also provided with a guide ring 24 for the same purpose and cable sections 25 are secured as shown to the guide ring 24. The cable sections 25 pass upwardly and outwardly through slots 26 in the sides of the section 19 and thence over guide pulleys 27 mounted in brackets 28 on the sides of said section. The lower ends of the section 25 are then brought together and secured to a clamp 29 to form a lifting bridle for the upper section 22, as will be readily understood. Lifting cable 30 is secured to the clamp 29 and passes downwardly under a guide pulley 31 mounted on the bracket 18 and thence to a hand winch 32 mounted on the truck as shown. By this arrangement, it will be noted, that the upper gin pole section 22 may be readily elevated or lowered when the lower section 19 is upright. An additional guide pulley 33 is arranged as shown on the bracket 18 to facilitate the use of another cable or rope and other lifting or lowering means for manipulating the upper section 22 when desired.

A raising cable 34 has one of its ends anchored at 35 to the lower section 19 and passes thence over a double floating pulley block 36, a stationary double pulley block 37 and a guide pulley 38 on a supporting frame 39 to a double hoisting drum 39 on the tractor 12 and operable in the usual way from the engine 13 whereby the lower gin pole section 19 may be readily raised into upright position or lowered into substantially horizontal position when desired. Suitable hooks 40 are provided on the sides of the section 19 for the attachment of guy ropes or cables to hold and brace the section in its upright position.

A four-armed bracket 41 is arranged as shown at the top of the upper section 22 for the connection of guy ropes or cables 42 for further securing the gin pole in its raised and extended position. A stop ring 43 is also provided near the top of the upper section 22 to limit the descent or telescoping action of the upper section in the lower section 19.

A supporting ring 44 is secured as shown in the top of the section 22 and provided with an upstanding nipple 45 on which is swivelled a supporting head 46 mounted to rotate freely on ball bearings 47. The supporting head 46 is provided with a laterally and upwardly extending bracket 48 supporting a guide pulley 49 over which passes a hoisting cable 50 provided at its end with the usual hoisting hook 51. The hoisting cable 50 extends downwardly through the

interior of the sections 22 and 19 and then outwardly under a guide pulley 51 supported on a bracket 52 secured as shown to the lower portion of the section 19 and thence to the hoisting drum 39 on the truck 12 as indicated.

By this arrangement, a gin pole construction is provided which may be readily telescoped and lowered for convenience in transportation, and quickly extended into substantially vertical position for use in the field and which is capable of economical production and highly efficient in use. The specific form and arrangement of parts is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. The combination of a truck body; a support in the form of a channel arranged transversely of said body; a tubular base member resting in the channel of said support; U-bolts clamping the ends of said base member in said support; a substantially U-shaped bracket embracing the central portion of said base member with its sides projecting upwardly; a gin pole having its lower end pivotally mounted between said bracket sides; and means on said truck for raising and lowering said gin pole.
2. A gin pole comprising a tubular base member; a U-shaped bracket pivotally embracing said member; a tubular lower pole section pivotally mounted in said bracket; a tubular upper pole section slidably mounted in said lower section; guide pulleys arranged diametrically at the top of said lower pole section, there being slots in the sides of the lower pole section registering with

said pulleys; two cable sections secured to the lower end of said upper pole section and passing outwardly through said slots and downwardly over said pulleys, said cable sections being secured together at their lower ends to form a bridle; a cable attached to said bridle; a guide pulley mounted on said U-shaped bracket and said last mentioned cable passing thereunder; an upwardly extending nipple connected with the top of said upper pole section; a supporting head swivelled on said nipple; a pulley bracket on said supporting head carrying a guide pulley; a hoisting cable passing over said last mentioned guide pulley and downwardly through said nipple and pole sections, there being a slot in the side of said lower pole section near its bottom; and a bracket secured to said lower pole section and carrying a guide pulley registering with said last mentioned slot, said hoisting cable passing outwardly through said last mentioned slot and under said last mentioned guide pulley.

3. The combination with a support, of a tubular lower pole section pivotally mounted on said support and having a stop ring secured around the inside of its top; means for pivotally adjusting said pole section on said support; an upper pole section sliding within said lower section and projecting from the top thereof; a stop ring secured around the outside of said upper pole section at its bottom and arranged to co-operate with the stop ring at the top of said lower pole section; guide pulleys arranged diametrically at the top of said lower pole section; two cable sections secured to the ring at the lower end of said upper section and passing outwardly and downwardly over said pulleys, said cable sections being secured together at their lower ends to form a bridle; a raising cable connected with said bridle for lowering and raising said upper pole section; and a hoisting cable operatively mounted on said pole sections.

HAROLD J. MARTIN.
